Primary Examiner — Lauren R Calve(74) *Attorney, Agent, or Firm* — Birch, Stewart, Kolasch & Birch, LLP(57) **CLAIM**

I claim the ornamental design for a hanger for clothing care machine, as shown and described.

DESCRIPTION

FIG. 1 is a perspective view of a hanger for clothing care machine showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view in a state of use thereof.

The broken lines in FIGS. 1 to 6 represent portions of the hanger for clothing care machine that form no part of the claimed design. The broken lines in FIG. 8 are included for the purpose of illustrating environmental structure and form no part of the claimed design.
